(57) **CLAIM**

The ornamental design for a speaker system with media player dock and rechargeable batteries, as shown and described.

DESCRIPTION

FIG. 1 is a top, front, side, perspective view of a speaker system with media player dock and rechargeable batteries showing my new design;

FIG. 2 is a front view thereof;

FIG. 3 is a rear view thereof;

FIG. 4 is a top view thereof;

FIG. 5 is a bottom view thereof;

FIG. 6 is a side view thereof; the opposite side view being a mirror image;

FIG. 7 is a cross-sectional view thereof along the line 7—7 in FIG. 2;

FIG. 8 is a cross-sectional view thereof along the line 8—8 in FIG. 4;

FIG. 9 is a top, front, side, perspective view thereof in an alternate condition;

FIG. 10 is a front view thereof;

FIG. 11 is a rear view thereof;

FIG. 12 is a top view thereof;

FIG. 13 is a bottom view thereof;

FIG. 14 is a side view thereof, the opposite side view being a mirror image; and,

FIG. 15 is a cross-sectional view thereof along the line 15—15 in FIG. 10.

The broken lines in the drawings illustrate environmental material that forms no part of the claimed design.
